CAN END CLOSURE ATTACHING MACHINE

Otto A. Schmitt, Syracuse, N. Y., assignor to
 Continental Can Company, Inc., New York,
 N. Y., a corporation of New York

Application November 10, 1939, Serial No. 303,991

12 Claims. (Cl. 113—19)

The invention relates generally to the art of manufacturing containers of sheet metal, or of a combination of sheet metal and paper or similar non-metallic body and end closure elements, and primarily seeks to provide a novel machine for assembling such body and end closure elements.

An object of the invention is to provide a machine of the character stated in which is embodied novel container body and end closure element feeding and positioning means and novel means for effecting adjustments in the relative positions of these equipments so as to adapt the machine for assembling containers of different sizes.

Another object of the invention is to provide a machine of the character stated embodying a novel turret structure having provision for holding the container bodies and the end closure elements in registering relation, novel means for bringing about a nested relation between each body and the associated end closure element while they are held on said turret, and novel means for moving the nested container parts into the zone of influence of a seam forming or sealing means for securing said closure elements on said bodies while they are supported by said turret.

Another object of the invention is to provide a machine of the character stated in which the turret structure includes novel holding elements for holding each end closure at edge portions thereof, and novel means for separating said elements to release said end closures as the nested container parts are moved into the zone of influence of the sealing means.

Another object of the invention is to provide a machine of the character stated in which the sealing devices are mounted in a housing which is swingably supported on the machine frame so that it can be readily moved into cooperative relation with the turret, or swung away from the turret in order to render the turret parts and said devices readily accessible for manipulation or replacement.

Another object of the invention is to provide a machine of the character stated in which is included power means for transmitting movement to the various mechanisms of the machine, and novel pneumatically actuated means for shutting off the power application whenever the proper complements of container parts is not being fed into the machine.

With the above and other objects in view that will hereinafter appear, the nature of the invention will be more fully understood by following

the detailed description, the appended claims, and the several views illustrated in the accompanying drawings.

In the drawings—

5 Figure 1 is a perspective view illustrating the machine.

Figure 2 is a vertical longitudinal section taken along the axis of the main drive shaft.

10 Figure 3 is a vertical longitudinal section of the machine taken through the axis of the seaming head.

Figure 4 is a fragmentary plan view and part horizontal section illustrating portions of the turret, the cross feed mechanism and the reciprocable pre-assembly plate and driving connections therefor.

Figure 5 is a vertical cross section of the machine, the section being taken between the seaming head and the turret looking toward the turret.

20 Figure 6 is a detail vertical longitudinal section through the container body feeding table.

Figure 7 is a horizontal section taken through the table illustrated in Figure 6, the section being taken through the axis of the table adjusting devices and parts being shown in plan view.

Figure 8 is an enlarged fragmentary plan view illustrating the mounting of the can body accelerating disks.

Figure 9 is a detail vertical cross section taken 30 on the line 9—9 on Figure 8.

Figure 10 is a detail vertical cross section taken on the line 10—10 on Figure 6.

Figure 11 is a fragmentary horizontal section illustrating the adjustable mounting of the container body end opposing sector.

Figure 12 is an enlarged fragmentary vertical longitudinal section taken through the axis of the turret and the end closure feeding mechanism.

40 Figure 13 is an enlarged detail horizontal section taken through the end closure feeding mechanism.

Figure 14 is a diagrammatic sectional view illustrating the mechanism for discontinuing operation of the machine whenever a proper complement of container body and end closure to be assembled is not present in the machine.

Figure 15 is a fragmentary horizontal sectional view illustrating the relation of a container body 50 and the end closure with which it is to be assembled just after the body has been fed into the turret pocket.

Figure 16 is a view similar to Figure 15 and illustrates the pre-assembly or nesting of the container body and its companion end closure.

Figure 17 is a fragmentary horizontal section of the securing station at the bottom of the turret and illustrates the seaming function or the step of securing the assembly of the container body and its companion end closure.

Figure 18 is a view similar to Figure 17 and illustrates the displacement of the assembled and secured container from the chuck and cooperating seaming rollers.

In the machine herein disclosed as an example of embodiment of the invention there is included a frame A, a motor or power source B, a clutch housing C, a clutch actuator housing D, and a pneumatic clutch actuator E. The machine also includes a vertically adjustable container body feed-in mechanism F, a cross feed mechanism G, a finished container feed-off way H, an end closure feed I, and a turret J and a sealing unit K disposed in opposed relation on horizontal axes.

The frame A includes a base portion 5 and an upper or main housing portion 6. Within the housing portion a main or power shaft 7 is rotatably supported in horizontal bearings 8.

The motor B imparts rotation to a driver pulley 9 composed of spring-pressed cone disks, and the rotation of this pulley is imparted through a V-belt 10 to the clutch drive pulley (not shown) disposed within the clutch housing C. The motor may be bodily moved through the medium of a screw adjusting means 11 in order to vary the driving ratio of the pulley equipments just mentioned so as to vary the speed of operation of the power shaft 7.

The main drive shaft 7 is hollow, and a clutch actuator rod 12 is longitudinally movable in said shaft and extends into the actuator housing D where it is secured to an annularly grooved head 13 splined as at 14 on the shaft 7. A shifter ring 15 is mounted in the head groove and is trunnion-connected with a shifting fork 16 secured upon a crank shaft 17 rockably mounted in bearings 18 supported on the frame 5 in the manner best illustrated in Figures 1 and 2 of the drawings. A crank 19 is affixed to the shaft 17 and is link-connected as at 20 to a crank 21 secured upon another crank shaft 22 rockably supported as at 23 on the frame in the manner illustrated in Figures 1 and 3 of the drawings. The crank shaft 22 carries a crank arm 24 which is link-connected as at 25 with one end of a piston rod 26 which has its other end secured to a piston 27 reciprocable within a cylinder 28 forming a part of the pneumatic actuator equipment E and secured as at 29 to the frame portion 6. See Figures 1 and 14 of the drawings.

The cylinder 28 is connected by a duct 30 with pneumatic control equipment later to be described and includes a slideway 31 traversed by an air vent 32. A venting slide 33 is mounted in the slideway and is equipped with a venting aperture 34, which, when aligned with the venting equipment 32, will serve to admit atmospheric air into the interior of the cylinder 28. The slide 33 is frictionally held against its seat by a spring-pressed plunger 35, and movement is imparted to this slide through the medium of an actuator rod 36. The rod 36 is freely straddled by a boss or fork 37 projecting from the link 25, and this boss is disposed between spaced stop collars 38 secured to said rod. The slide 33 is normally positioned as illustrated in Figure 14, and in this normal position the venting apertures are out of registry and the cylinder 28 is closed against ingress of atmospheric air. In this condition of the parts it will be obvious that upon evacuation of the cylinder 28 through the conduit 30, the

piston 27 will be drawn to the left and the link 25 and the remaining crank and link connections will be actuated to move the de-clutching rod 12 longitudinally within the shaft 7 for the purpose of disengaging the clutch and discontinuing operation of the machine. The collars 38 are so spaced that when this de-clutching operation is effected, movement of the fork 37 to the left, as viewed in Figure 14, will not effect an atmospheric venting of the cylinder 28.

When operation of the machine has been automatically discontinued, the operator may manually shift the rod 36 to cause the aperture equipments 32 and 34 to communicate and allow air to enter the cylinder 28 so that the piston 27 can be restored to its normal position illustrated in Figure 14. Restoration of the piston to its normal position will cause the fork 37 to contact the outermost collar 38 and restore the slide 33 to the vent closing position illustrated in Figure 14.

A hand lever 39 may be actuated for manually effecting a de-clutching action and discontinuing the operation of the machine if desired.

The can body feed-in mechanism F includes a table 40 having rigidly mounted, vertically disposed bearings 41 and 42 thereon. The vertical bearing members 41 and 42, respectively, surround a vertical shaft 43 and a vertical sleeve 44, the former including a threaded part 45 threadably received in a bearing 46 stationarily supported on the frame portion 6, and the latter including a threaded portion 47 threadably received in a bearing 48 stationarily mounted on said frame portion. A worm wheel 49 is secured to each of the elements 43 and 44, and each said worm wheel is engaged by a worm gear 50 mounted on a short cross shaft 51 rotatably supported in a bearing 52 and connected by a bevel pinion couple 53 with a manually operable adjuster shaft 54 rotatably supported in bearings 55 secured upon the table and equipped with a hand wheel 56. See Figures 1, 6 and 7 to 9.

The rectangular container bodies or open-ended sleeves 57 are fed onto the table by laterally spaced feeder chains 58 which pass over driver sprockets 59 secured upon a cross shaft 60. This shaft is rotatably supported at the front end of the table and has a driver sprocket 61 affixed to one end thereof and a cam member 62 affixed to its other end. See Figures 6, 7, 8 and 9. The rotating cam member 62 is adapted to alternately lift and lower a roller 63 and the end of the lever 64 to which said roller is affixed. The lever is spring-depressed and is pivoted intermediate its ends as at 65 on the table. The front end of the lever 64 is link-connected as at 66 with one arm of a bell crank lever 67 rockably supported in a bearing member 68 vertically adjustably secured at the front end of the table, and the other arm of the bell crank lever carries a vertically adjustable stop member 69 adapted to be alternately projected into and removed from a position for obstructing free movement of the container bodies 57 on the conveyor chains 58.

The vertical oscillations of the stop member 69 are so timed that each time this member is in its lowered position it will intercept temporarily and hold an inwardly traveling container body 57 in the space between two laterally spaced housings 70 in the manner illustrated in Figures 8 and 9 of the drawings. Each housing member includes spaced wall portions 71 forming lateral guides for the traveling can bodies and is adjustably supported as at 72 so that the spaced relation of the housings can be varied. Beneath the housings the table is equipped with a pair of laterally

aligned slideways 73 in each of which a bearing block 74 is slidably mounted. Each block 74 includes a vertically disposed bearing portion 75 in which is rotatably mounted a shaft member 76, and a horizontally disposed bearing portion 77 in which is rotatably mounted a sleeve 78 equipped with a bevel pinion 79, said sleeves surrounding and being spline-connected to the cross shaft 60 hereinbefore referred to. Adjusting devices 80 are provided for moving the blocks 74 in the slideways 73, and by this means the spaced relation of the shafts 76 can be adjusted. A bevel pinion 81 is secured to the lower end of each shaft 76 and meshes with the bevel pinion 79 of the adjacent sleeve 78, and by this means the rotation of the shaft 60 is imparted to the spaced vertical shafts 76.

A feed wheel 82 is secured upon the upper end of each shaft 76, and each wheel carries a feeder segment 83 grooved to straddle the reduced side guide wall portion of the casing in the manner illustrated in Figure 9 of the drawings and disposed to oppose and cooperate with the segment of the companion wheel in yieldably gripping and imparting accelerated feed movement to the can bodies in the manner illustrated in Figures 8 and 9 of the drawings. The can bodies 57 are fed into the machine in a continuous line by the chains 58, the line of cans being alternately intercepted and then released by the vertically oscillating stop member 69. Each time the stop 69 is moved up to release the can bodies the segments 83 engage the side walls of the foremost can body in the line and rapidly move it away from the line while the stop member is elevated and feeds it into the zone of influence of the other feeding devices of the table. Immediately after the feeder segments have thus separated the foremost can body from the remainder of the line, the stop member 69 will descend and again intercept the line of can bodies.

A feed bar 84 is reciprocably mounted in a receiving grooveway 85 formed in the table and carries a fixed feed finger 86 at its front end and equi-distantly spaced series of spring-elevated feed fingers 87 throughout the remainder of its length. The feed bar is flanked at its respective sides with guide rails 88 which are adjustably supported as at 89 on the table so that their spaced relation can be altered. A guard rail 90 is disposed in spaced relation above the feed bar and carries a plurality of gravity depressed back check fingers 91 which function to hold can bodies in the positions to which they have been fed each time the feed bar is retracted for a new feeding stroke. The guard rail also includes a spring-depressed back check finger 92 disposed in cooperative relation above the fixed finger 86 and which is displaced by each can body as it is rapidly moved into the feed line by the rotating wheels 82.

The main shaft 7 has a worm gear 93 affixed thereon which meshes with a worm wheel 94 on a cam shaft 95 rotatably supported in vertically aligned bearings 96 and 97, respectively, provided in the base frame and the frame housing portion 6. Spur gears 98 and 99 are affixed to the shaft 95 and this shaft also carries a grooved plate cam 100, a grooved drum cam 101, a spur gear 102, and a grooved plate cam 103 in the manner best illustrated in Figure 3 of the drawings, the purpose for all of which will be disclosed hereinafter.

The spur gear 99 meshes with a spur gear 104 on a shaft 105 rotatably supported in a vertical-

ly disposed bearing 106 in the frame housing 6 and having a cam 107 affixed to the upper end thereof. The purpose of this cam will later become apparent.

5 The spur gear 104 meshes with a spur gear 108 secured upon a shaft 109 splined in the gear 108 and vertically rotatable within the screw sleeve 44 hereinbefore referred to. The shaft 109 carries a spur gear 110 at its upper end which includes an off-center crank pin 111 on which a crank member 112 and an integral or rigidly connected pinion 113 are rotatably mounted. The pinion 113 meshes with the integral ring gear 114 which is fixedly mounted as at 115 on the table. 10 The crank member 112 is connected by an adjustable link 116 with a bracket member 117 secured to and depending from the feed bar 84.

15 The pinion 113 is so proportioned with relation to the ring gear within which it meshes that as it is rotated about within said ring gear the position of the crank member 112 will constantly be altered so that its pivotal connection with the link 116 will always move in a straight line centered on the feed bar slideway, and by this means the rotary motion of the vertically disposed shaft 109 is transmitted in the form of the desired straight line reciprocation to the feed bar 84.

20 The spur gear 110 meshes with a pinion 118 mounted on a shaft rotatable in a vertically disposed bearing 119 secured upon the table and connected by a bevel gear couple 120 with a shaft 121 having rotatable bearing in a portion of the same bearing member 119 and in a bearing 122 secured as at 123 on the table. The bearing 122 also rotatably supports a short shaft 124 which is bevel gear coupled as at 125 with the shaft 121 and carries a driver sprocket which is chain connected as at 126 with the driven sprocket 61 on shaft 60 hereinbefore referred to for the purpose of imparting rotation to the shaft 60. See Figures 6, 7, 8 and 9 of the drawings.

25 The guard rail 90 is supported on a bracket arm 127 which is pivotally mounted as at 128 on a standard 129 vertically-slidably secured as at 130 on the table in the manner illustrated in Figure 10 of the drawings. Vertical adjustment of the standard 129 may be effected through the medium of an adjuster screw 131 which is 30 threaded through a lug portion of the standard and engages an abutment block 132 affixed to the table. It will be obvious by reference to Figure 10 that the can body guiding rails 88 can be adjusted laterally to accommodate can bodies of 35 different sizes, and this adjustment can be accompanied by a vertical adjustment of the guard rail 90. The guard rail 90 may also be freely 40 swung upwardly about its pivotal mounting 128.

The turret J comprises a plate or disk body 133 having a plurality (eight being shown) of equidistantly spaced peripheral pockets 134. Each pocket is flanked by slideways 135 in which opposed jaw members 136 are slidably mounted. Pin and slot equipments 137 limit movement of the jaws toward each other, and each opposed pair of jaws is spring-urged toward each other to the limit permitted by said pin and slot equipments by compression spring equipments 138. The opposed edges of the jaws are grooved as at 139 (Figs. 15 to 18) to receive and retain the edges of end closures fed into the pockets in the manner hereinafter to be described.

70 The disk or body 133 is riveted to a supporting sleeve 140 secured by a removably mounted sleeve 75

141 and screw equipment 142 to the end of a turret sleeve 143 rotatably supported in a horizontal bearing 144 provided therefor in the machine frame. The shaft 143 carries a disk 145 at its other end, and a plurality (eight in this disclosure) of equi-distantly spaced rollers 146 project from this disk in the manner illustrated in Figures 3 and 12 of the drawings. Pintles 147 project rearwardly from a flange on the sleeve 143 through selectively positioned spacer sleeves 148. These sleeves are selectively positioned in the manner best illustrated in Figures 3 and 12 of the drawings to alter the spaced relation between the disk 133 and a body supporting disk 149 which is equipped with peripheral pockets 150 aligned with those of the disk and is adapted to support the rear ends of the container bodies 57 in the manner illustrated in Figures 3 and 15 through 18 of the drawings. It will be observed by reference to these figures of the drawings that the disk pockets support the front ends of the container bodies.

In practice, one of the sleeves 148 is made one inch in length, another $\frac{1}{8}$ of an inch, and the third $\frac{1}{2}$ inch in length. It will be obvious that by changing the positions of the members 148 on the supporting sleeve 143 the position of the disk 149 with respect to the disk 133 can be altered to best suit the size of can body being operated upon at the particular time.

The turret is indexed by an indexing cam 151 which engages the indexing rollers 146 in the manner illustrated in Figures 3 and 12 and operates in a manner well-known in the art for moving the turret through successive steps to present the turret pockets at successive stations and to hold the turret for an interval at the indexed positions while the various operations incident to assembly of the container parts are effected. The cam 151 is mounted on the upper end of a shaft 152 rotatably supported in a vertical bearing 153 on the frame, and this shaft carries a spur gear 154 at its lower end which meshes with the spur gear 152 within the frame housing portion 6.

A concentric track sector 155 opposes the open pockets of the turret over about half the lower portion of the turret in the manner best illustrated in Figures 3 and 5 of the drawings, and this sector is removably secured as at 156 upon the portion 6 of the machine frame. This sector 155 forms a closure for the peripherally open turret pockets in which the container bodies travel and serves to prevent any radial displacement of the container bodies while travelling about the lower half of the turret travel.

Upon a housing or super-structure framing 157 an end closure stack 158 is hingedly mounted as at 159. The stack provides a vertical way in which a stack of container end closures 160 are supported on spring-pressed fingers 161. A vertical slideway 162 is provided beneath the stack, and a slide member 163 is reciprocably mounted in this slideway and carries a suction cup 164 at its upper end adapted to be alternately engaged with and withdrawn from contact with the stack of end closures for the purpose of individually withdrawing closure members from the stack.

The slide 163 includes a suction duct 165 which communicates at one end in the suction cup 164 and is connected by a conduit 166 with the interior of a valve plate 167 spring-urged as at 168 against a valve member 169 freely rotatable about a stationary stud shaft 170 on which said valve plate 167 is mounted and held against rotation.

This valve equipment serves to time suction communication between the suction cup 164 and a suction source in a manner soon to be described. The interior coring of the valve plate 167 is connected by a conduit 171 with the interior of a valve structure 172 mounted on the guard rail 90, and the valve structure 172 also has a conduit connection 173 with the suction source conduit 174 leading to an evacuating pump or other source of negative pressure (not shown).

5 The valve structure 172 is equipped with a seat 175 between the duct connections 171 and 173, and a valve member 176 cooperates with this seat to permit or prevent communication between said ducts. The valve member 176 is mounted on a plunger 177 and is normally pressed against its seat by a compression spring 178. The plunger is connected by a link 179 with one arm of a bell crank lever 180 which is pivoted at 181 on the guard rail 90 and includes a horizontal arm or leg portion 182 positioned as illustrated in Figures 6 and 14 of the drawings for being lifted by a can body 57 entering the zone of influence of the feed bar 84 in the manner clearly indicated in Figure 14.

20 Each time an incoming can body lifts the bell crank arm 182 and opens the valve 176, suction communication is afforded through the ducts 174, 173, 171; the control valve equipments 167 and 169; and the ducts 166 and 165, so that when the suction cup 164 is pressed against the bottom of the stack of end closures 160 and again withdrawn from contact with the stack it will remove the lowermost closure from the stack and move it downwardly. It will be understood, of course, 25 that the communication through the various ducts and passages just referred to is properly timed by the valve 169 which is rotated in timed relation with the other feeding devices.

30 Each end closure thus withdrawn from the bottom of the stack is deposited on a pair of horizontally disposed laterally spaced conveyor chains 183 which pass over sprockets 184 on an idler shaft 185 rotatably supported in the housing 157 and over driver sprockets 186 mounted 35 on a driven shaft 187 rotatably supported in said housing. The shaft 187 may be manually rotated by use of a hand wheel 188 affixed thereto, but during the normal operation of the machine it is actuated mechanically and in suitably timed relation with the other mechanisms of the machine. The shaft has a spring-pressed overload release drive head 189 keyed thereon which yieldably holds driving and drive releasing balls 190 40 in seats or recesses on a spur gear 191 freely rotatable about the shaft 187 and adapted to be driven by an intermeshing small spur gear 192 keyed on a sprocket sleeve 193 secured to the valve rotor 169 and driven by a chain connection 194 with a sprocket on the cross shaft 195 rotatably supported as at 196 in the housing 157. The shaft 195 is driven by a bevel pinion couple 197 with the upper end of the shaft 105.

45 A cam 198 is secured on the shaft 195 and engages a roller 199 mounted on one end of a lever 200 which is pivotally supported intermediate its ends as at 201 and has its other end connected as at 202 with the suction cup actuated slide member 163. This lever is urged to its slide lowered position by a tension spring 203. The shaft 195 also carries a grooved plate cam 204 the purpose of which will later become apparent.

50 Container end closure feeding lugs 205 project from the chains 183, and these lugs engage the end closures individually deposited on the chains

183 by the suction cup 164 and individually deliver the end closures into the downwardly curved guide or chute portions 206 from whence they are delivered into the vertically disposed guideways 207 mounted on a frame plate 208 which is secured in vertical position upon the housing 157 directly in advance of and close to the upper portion of the turret. See Figures 5, 12 and 13.

The plate 208 is provided with an opening 209 (Fig. 14) which registers with the uppermost turret pocket presented one station beyond the vertical in the direction in which the turret moves. This comprises a test station at which means is positioned for detecting the presence or absence of an end closure in the turret pocket presented at that station.

The plate 208 supports a valve structure 210 in the manner best illustrated in Figures 12 and 13 of the drawings, and this valve is connected by the duct 30 with the clutch control cylinder 28 and by another duct 211 with a similar valve structure 212 secured upon the guard rail 90. It will be noted that the ducts 30 and 211 of the valve structure 210 are disposed in spaced relation, and that the valve structure 212 is connected by a duct 213 with the suction source duct 174, said duct 213 being similarly spaced from the duct 211. A seat 214 is interposed between the ducts 211 and 213 within the valve structure 212, and passage through this valve structure is controlled by a valve member 215 which cooperates with said seat and is carried by a plunger member 216. The valve member 215 is urged toward its seat by a compression spring 217, and the plunger is connected to one arm of a bell crank lever 218 pivoted as at 219 on the guard rail 90 and including a horizontally disposed arm or leg portion 220 adapted to be actuated by a container body 57 for unseating the valve member 215 in the manner illustrated in Figure 14.

The valve structure 210 also includes a seat 221 interposed between the ducts 30 and 211 and controlled by a valve member 222 carried by a plunger 223 spring urged in the valve seating direction by a compression spring 224 and having an abutment head 225 thereon. A feeler head 226 is movable in the plate opening 209 so as to be projectible into and retractible from turret pockets presented at the testing station in the manner illustrated in Figure 14. The head 226 is mounted on a plunger 227 which is slide-guided as at 228 on the valve structure 210 and has an abutment ear 229 straddling the valve plunger 223. The rod 227 also has an abutment collar 230 thereon, and a block 231 is slidably mounted on said plunger and yieldably held against the collar 230 by a compression spring 232.

A crank shaft 233 is rockably supported on the plate 208 and has a depending crank 234 which is slot and pin connected as at 235 with the block 231. It will be obvious by reference to Figure 14 of the drawings that as the crank 234 is moved to the left it will move the feeler head 226 into the turret pocket presented at the test station. Should no container end closure 160 be present in the pocket the head would move freely into the pocket and the abutment ear 229 would engage the valve rod abutment 225 and unseat the valve member 222. Whenever a container end closure is present in the turret pocket, the feeler head will engage it in the manner illustrated in Figure 14 and further movement of the head will be arrested. When movement of the feeler

head 226 is thus normally arrested by presence of a container end closure in the turret pocket, normal additional movement of the crank arm 234 is permitted by sliding of the block 231 and compression of the spring 235. The rock shaft 233 also carries a crank 236 connected with a thrust link 237 equipped with a roller 238 at its other end which rides in the groove in the plate cam 204. It will be obvious that rotation of the cam 204 imparts the desired oscillation to the crank member 234. See Figures 1, 13 and 14.

In a horizontal slideway 329 formed on the machine, a cross slide 240 is reciprocably mounted. One end of a link 241 is pivotally connected to the slide as at 242 and the other end of this link is pivotally connected as at 243 with a crank arm 244 secured upon the upper end of a shaft 245 rockably mounted in bearings vertically disposed on the frame. At its lower end, the shaft 245 carries a crank arm 246 which is link-connected as at 247 with a crank disk 248 adjustably secured to an idler gear 249 meshing with the gear 98 hereinbefore referred to. The cross slide 240 has a feed arm 250 secured to one end thereof, and this arm functions to feed container bodies laterally off the feed table 40 and into the turret pockets as they are presented in horizontal position in the manner best illustrated in Figure 5 of the drawings. See also Figures 4 and 12.

The various feeding devices for the container bodies 57, the end closures 160 and the turret are so cooperatively timed that each container body 57 which actuates the bell crank lever arm 182 and the valve member 176 connected therewith will so control the feeding of an end closure 160 that that particular end closure and the container body which controlled its feeding will be brought together as a closure and container body complement in a particular turret pocket. The same container body 57 which actuated the bell crank lever arm 182 for controlling the feeding of the particular end closure to be applied to that particular container body, also actuates the bell crank lever arm 220 when the presence or absence of an end closure in the particular turret pocket timed to receive that particular container body is being tested in the manner diagrammatically illustrated in Figure 14. It will be observed also that the valve structures 210 and 212 are connected in series with the declutching mechanism actuating cylinder 28. Thus both of the valve members 222 and 215 must be unseated by the absence of an end closure and the presence of a container body in order to pneumatically effect a declutching actuation and a stoppage of the machine operation. In this manner the operation of the machine will be stopped whenever proper complements of container bodies and end closures are not in proper position to be moved into assembled relation in the turret pockets. Whenever the machine is stopped by a test indicating the absence of an end closure in the particular turret pocket which is to receive the container body engaging the bell crank lever arm 220 at the time the test is made, and it is desired to normally continue operation of the machine, the operator has but to manually insert an end closure 160 in the empty pocket and re-start the machine in the manner hereinbefore described.

At its left hand end, as viewed in Figure 5, the cross slide 240 carries a pair of spaced stripper or discharge fingers 251 which are adjustably supported as at 252 on said slide. It will be obvious by reference to Figures 4 and 5 of the drawings that each time the cross slide moves to the left

as viewed in these figures the feeder element 250 and discharge fingers 251 carried thereby will respectively function to feed a container body 57 into a horizontally presented turret pocket and remove or discharge a finished or completely assembled container and end closure from the turret pocket horizontally presented at the opposite side of the turret.

As a container body is fed into a turret pocket in the manner just above described the rear end is opposed by a pre-assembling or nesting plate 253 which is mounted on a carrier 254 adjustably secured as at 255 on a slide member 256 guided as at 257 on the frame in the manner best illustrated in Figure 4 of the drawings. The slide 256 carries a roller 258 and is yieldably urged by a spring 259 against the cam 107 mounted on the upper end of the shaft 105 as hereinbefore described.

Each end closure member usually includes a depressed central portion dimensioned to fit snugly within the end of the container body with which it is to be assembled, and because of this projection of the central portion of the end closures it is necessary to initially position the bodies and end closures in spaced relation in the pockets in the manner illustrated in Figure 16 of the drawings. Thus it is necessary to bring about relative endwise movement between the complementary container elements in order to properly nest them prior to permanent assembly thereof in the manner illustrated in Figure 16. This pre-assembly or nesting function is accomplished by reciprocation of the plate 253, and this plate is reciprocated by action of the rotary cam 107. By adjustably mounting the plate 253 it can be made to cooperate with container bodies of different lengths.

Following the pre-assembly or nesting of the complementary container elements at the stations at which the container bodies are received in the turret pockets and before the container elements are permanently secured in assembly at the securing station, the rear ends of the containers are opposed by a stationary abutment sector 260 having its abutment face disposed flush with the like face of the pre-assembling plate 253 when it is positioned at the completion of its nesting function. See Figure 4. The sector 260 is carried on a shank 261 spline-connected as at 262 to a portion of the machine frame and threaded through a worm wheel 263 engaged by a worm gear 264 mounted on an adjuster shaft 265 having rotative bearing in the frame in the manner best illustrated in Figure 11 of the drawings. By manipulation of the shaft 265 through the medium of a suitable hand wheel 266, adjustment of the position of the sector 260 can be effected so as to present it in guiding or end abutting relation with turret pocket carried container bodies of different lengths.

When the turret pockets are presented at the lowermost vertical position they are presented at the securing station, at which station the end closures are permanently secured to the container bodies by a seaming operation. It is to be understood that when the containers are intended for the packaging of products which require them to be gas or liquid tight, this securing operation will probably take the form of a double seam securing operation. When the containers are intended for the packaging of granular materials or products not requiring such secure sealing, the securing function may take the form of a false seaming operation in which it is necessary only to effect a permanent attachment of the end closure

and the complementary container body. In its broadest aspects the invention comprehends these and other container body and closure securing functions.

- 5 At the securing station a vertical slideway 267 is provided beneath the turret and in this slideway a slide member 268 is vertically reciprocable. The slide is engaged by the forward end of a lever 269 which is pivoted intermediate its ends as at 270 on the frame and has its rearmost end 10 as at 270 on the frame and has its rearmost end equipped with a roller 271 which rides in the groove in the drum cam 101, thereby serving to impart the desired reciprocation to the slide 268 in suitably timed relation with the turret movements so that the slide will be moved toward the turret each time a turret pocket comes to rest at the securing station. At its upper end the slide 268 carries a removably mounted wedge piece 272 which engages between opposed jaws 136 presented at the securing station for the purpose of spreading the jaws from the position indicated in Figure 16 of the drawings to the positions illustrated in Figures 17 and 18 to thereby free the edges of the end closure 160 now held by nesting in the front end of the container body 57. It will be observed that the wedge piece 272 is shaped to form a completion of the turret pocket presented at the securing station, and this element aids the turret disk 133, the turret plate 149 and the sector 155 in properly supporting the container parts at the securing station.

After the jaws 136 have been separated and the pocket completed by presentation of the wedge piece 272, a container chucking pad 273 supported 35 on the end of a screw member 274 is forced against the end of the container to slide the container in the turret pocket forwardly against the chuck of the seaming head. The screw member 274 is threaded in a sleeve 275 slide-guided 40 as at 276 on the frame and having a depending roller 277 engaged in the groove of the plate cam 103. It will be obvious by reference to Figure 3 of the drawings that the plate cam imparts the desired reciprocation to the chucking pad 273 and that the position of the pad can be 45 readily adjusted by threading the screw member in the sleeve 275 so as to position the pad for proper engagement with container bodies of different lengths.

50 The take-off way H includes a supporting table 278 upon which are mounted guide rails 279 disposed in adjustably spaced relation in the manner best illustrated in Figures 1, 4 and 5 of the drawings. A screw member 280 supports the table 278 and is threadably adjustable in a bearing arm 281 swingably mounted as at 282 upon the frame. Thus the take-off way H is mounted for vertical adjustment so that it can be properly positioned with respect to containers of different sizes presented at the discharge station, and this way H 60 can also be swingably displaced so as to facilitate access to machine parts thereadjacent. See Figures 1 to 5.

The frame 6 includes a step portion 283 65 equipped with a vertically disposed bearing 284, as is best shown in Figures 1, 2 and 3 of the drawings. The seaming head employed in this machine is horizontally disposed with an open end portion opposed to the lower portion of the turret in the manner illustrated in Figures 1 and 3 of the drawings. This seaming head is composed of upper and lower separable casing sections 285 and 286, a portion of the upper section being hingedly supported on the lower section as at 287. The lower section of the seaming

head casing is affixed to a depending hollow standard 288 which is swingably mounted in the bearing 284, and the seaming head is supported on anti-friction bearings 289 interposed between the head and said bearing. It will be noted by reference to Figures 1, 2 and 3 of the drawings that the vertical axis about which the seaming head is swingably mounted is disposed to one side of the axis of the turret and also to one side of the axis of the main portion of the seaming head. By thus swingably mounting the seaming head about an axis disposed in the particular manner stated, the seaming head can be completely swung away from its cooperative relation with the turret illustrated in Figure 3 of the drawings so as to facilitate access to and manipulation of turret and seaming head parts.

In order to prevent setting up of twisting stresses in the seaming head during movement thereof between operative and inoperative position, a rest boss 290 is provided on the lower casing section in position for riding over and being supported on an arcuate support step 291 projecting upwardly from the frame part 6.

A securing lug 292 projects from the lower casing section for receiving a hinged securing screw 293 pivotally supported on a portion of the frame. This quick detachable securing screw means serves to secure the seaming head in the operative position illustrated in Figures 1 and 3 of the drawings.

As has been hereinbefore stated, the securing means employed in this machine may be of any approved type, and when a securing means of the seam forming type is employed it may be of a type for providing a false seam or a double roll seam as hereinbefore stated. Any suitable form of square can seam forming mechanism may be employed, and the specific details of construction and operation of the seaming mechanism herein disclosed will not be dwelt upon at length herein because this seaming mechanism is fully illustrated and described in the co-pending application for U. S. Letters Patent filed November 27, 1939, by Alfred L. Kronquest and Otto A. Schmitt, and identified by Serial No. 306,366, now Patent No. 2,271,153, granted January 27, 1942.

The specific seaming mechanism referred to includes a stationary sleeve 294 which supports a chuck and cam unit 295. This unit includes a grooveway conforming to the shape of the can ends and serving the purpose of determining the positions of pivotally mounted supporting arms, said arms being pivotally mounted at their ends as at 296 in a rotor 297. The supporting arms support the seaming roller carrying arms 298 which are moved toward the chuck by cam elements mounted on the ends of shafts 299 rotatable about the axes of the pivotal supports 296 and driven by pinions 300 meshing with a large spur gear 301 fixed to a sleeve carrying a spur gear 302. The rotor 297 is fixed to a sleeve 303 having a gear 304 affixed thereto, and the gears 302 and 304 respectively mesh with spur gears 305 and 306 mounted on the sleeve 307 which is rotatable about a stud 308 fixedly supported in the seaming head casing. The sleeve 307 also carries a bevel gear 309 which meshes with a bevel gear 310 secured upon the upper end of a shaft 311 rotatably supported in bearings mounted in the pivot standard 288 of the seaming head. At its lower end the shaft 311 carries a bevel gear 312 to which rotation is imparted by a bevel gear 313 carried by the main shaft 7.

A knockout rod 314 is reciprocable in and

through the stationary sleeve 294, and this rod is connected at its front end with one end of a lever 315 which is pivoted intermediate its ends on a bracket 316 secured to the seaming head.

5 At its lower end the lever 315 has a quick release connection 317 with a link member 318 pivotally connected to a thrust-element 319 slide-guided as at 320 in the frame and equipped at its rear end with a roller 321 which engages in the groove 10 in the plate cam 100. Rotation of this cam imparts movement to the knockout rod 314 for at the proper time displacing from the chuck a can which has had its end closure securely fixed thereupon. See Figure 18 of the drawings.

In operation, the container bodies are fed onto the feed-in table in a continuous line in the manner indicated in Figure 8 of the drawings. The infeeding line of container bodies is intercepted by the depressed stop member 69 until the accelerating segments 83 are about to contact the most advanced container body in the manner indicated in said Figure 8. At this time the stop member 69 is lifted to free the container body and it is rapidly moved away from the line of 15 incoming can bodies by the rotating segments 83 and fed into the zone of influence of the feed bar 84.

As the container body moves under the guard rail 90 and over the feed bar 84 it displaces the 20 spring depressed detent 92 and rides over the fixedly mounted detent 86 on the feed bar 84. As it attains this position the can body actuates the bell crank lever 180 and displaces the valve member 176 thereby opening suction communication 25 through the ducts 174, 173, 171 so that when the rotary valve 169 effects a communication with the duct 166, a suction will be created at the suction cup and the reciprocating cup will withdraw the lowermost end closure 160 and deposit it on 30 the feed chains 183 so that it will be deposited in the turret pocket which is to receive the container body which controlled the feeding of said end closure.

The parts are so timed that when the turret 35 has advanced from the end closure receiving station to the next or end closure presence testing station, the container body which controlled the withdrawal from the supply stack of the particular end closure contained in that pocket will 40 have been advanced to the control station illustrated at the left end of the feed line portion shown in Figure 14. At this testing station, the feeler head 226 is moved into the turret pocket in the manner hereinbefore described, and the end closure 160 in that pocket will intercept its 45 movement in the manner illustrated in Figure 14 so that the valve member 222 will not be displaced for the purpose of opening suction communication. It will be noted, however, that each 50 time a can body arrives at the control station stated it will effect unseating of the valve member 215. With the valve member 215 thus displaced by the container body which is to be fed into the pocket now positioned at the test station, should no end closure be present in the pocket, due to faulty operation of machine parts or the 55 exhausting of the supply of end closures, the feeler head 226 will move full stroke into the turret pocket and the lug 229 movable therewith will act to unseat the valve member 222, thus 60 opening suction communication through both valve structures 210 and 212, the ducts 174, 173 and 30, thereby evacuating the cylinder 28 65 and bringing about a declutching of the motor 70

and an automatic stopping of the machine operation.

If it is desired to continue operation of the machine, the operator can manually insert an end closure 160 in the empty pocket so that a proper complement of can body and end closure will be presented for ultimate assembly, after which he will manually shift the slide 33 to vent the cylinder 28 and then manually reset the clutch to again start the machine. In manually resetting the clutch, atmospheric communication through the ports 32 and 34 will be broken by automatic shifting of the slide 33 in the manner hereinbefore described.

As the turret pocket bearing the end closure advances from the testing station into horizontal position at the container body receiving station, the particular container body which co-operated in the testing of the presence of said end closure will be shifted by the arm 250 into said pocket. While the turret still is at rest at this station, the pre-assembling plate 253 functions in the manner hereinbefore described and illustrated in Figures 15 and 16 of the drawings to effect a pre-assembly or nesting of the container body 57 and end closure 160 supported in the turret pocket.

As the turret moves from the container body receiving station toward the securing station, the abutment sector 260 opposes the rear end of the temporarily assembled container and confines it against displacement in the pocket, and as the turret pocket is presented at the securing station the container is registered with the chuck of the seaming mechanism and with the chucking pad 273.

After the turret comes to rest at the securing station the wedge plate 272 is elevated to separate the jaws 136 and free the edges of the end closure from the grooves 139 therein, and the element 272 is held against the turret and serves to complete the support and confinement of the container in the pocket during the seaming operation next to follow. After the jaws have been separated in the manner stated, chucking pad 273 is actuated to force the loosely assembled container parts into engagement with the chuck between the seaming rollers in the manner illustrated in Figure 17 of the drawings. With the parts in this condition the seaming or end closure securing function is completed in the manner illustrated in Figure 17, after which the slide 272 and the chucking pad 273 are returned to their normal positions and the cam 100 actuates the knockout rod to displace the finished container in the manner illustrated in Figure 18.

When the pocket containing the finished container reaches the horizontal position at the discharge station it is ejected from the pocket by the cross arm carried feeder arm 251 and enters the feed-off way H between the side rails 279.

It is of course to be understood that the details of structure and arrangement of parts may be variously changed and modified without departing from the spirit and scope of my invention.

I claim:

1. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed

separable jaw elements in part defining each disk pocket and having closure edge retaining grooves therein, and a container body supporting plate spaced along the turret axis from said disk and having peripheral pockets therein aligned with said disk pockets and cooperating therewith in supporting container bodies for sliding movement toward closures positioned in said jaw grooves.

5 2. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed 15 jaw elements in part defining each disk pocket and having closure edge retaining grooves therein, and a container body supporting plate spaced along the turret axis from said disk and having peripheral pockets therein aligned with said disk pockets and cooperating therewith in supporting container bodies for sliding movement toward closures positioned in said jaw grooves, said jaws being circumferentially slidable for movement into and out of the normal end closure retaining position, and spring means normally holding said jaws in the normal position.

3. In a machine of the character described, a turret structure comprising a circular disk having a plurality of equidistantly spaced container body receiving pockets in its periphery, means 35 mounting the turret for rotation about a horizontal axis, means for indexing turret for presenting the disk pockets at container closure and body receiving stations and at assembled container securing and discharging stations, opposed 40 separable jaw elements in part defining each disk pocket and having closure edge retaining grooves therein, and a container body supporting plate spaced along the turret axis from said disk and having peripheral pockets therein aligned with 45 said disk pockets and cooperating therewith in supporting container bodies for sliding movement toward closures positioned in said jaw grooves, and means for holding the supporting plate at various distances from the disk for properly supporting container bodies of different length.

4. In a machine of the character described, a turret structure comprising a circular disk having a plurality of equidistantly spaced container body receiving pockets in its periphery, means mounting the turret for rotation about a horizontal 55 axis, means for indexing turret for presenting the disk pockets at container closure and body receiving stations and at assembled container securing and discharging stations, opposed separable 60 jaw elements in part defining each disk pocket and having closure edge retaining grooves therein, and a container body supporting plate spaced along the turret axis from said disk and having peripheral pockets therein aligned with 65 said disk pockets and cooperating therewith in supporting container bodies for sliding movement toward closures positioned in said jaw grooves, and means for holding the supporting plate at various distances from the disk for properly supporting container bodies of different length, said last named means including a hub on which the plate is removably mounted, and a plurality of spacer rings of different length surrounding said hub with the plate between selected pairs thereof.

75 5. In a machine of the character described, a

turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed jaw elements in part defining each disk pocket and having closure edge retaining grooves therein, and a container body supporting plate spaced along the turret axis from said disk and having peripheral pockets therein aligned with said disk pockets and cooperating therewith in supporting container bodies for sliding movement toward closures positioned in said jaw grooves, said jaws being circumferentially slid-able for movement into and out of the normal end closure retaining position, spring means normally holding said jaws in the normal position, assembled container and closure securing means opposed to the turret at the securing station and comprising a seaming head including a chuck and cooperating seaming rollers, and means at the securing station for separating the grooved jaws presented thereat and for forcing the body and closure assembly against the chuck.

6. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed separable jaw elements in part defining each disk pocket and having closure edge retaining grooves therein, a container body supporting plate spaced along the turret axis from said disk and having peripheral pockets therein aligned with said disk pockets and cooperating therewith in supporting container bodies for sliding movement toward closures positioned in said jaw grooves, means for securing the closure members to the body members at the securing station and including a chuck engageable by preassembled closure and body members for definitely placing said pre-assembly relative to said securing means, a pre-assembling pusher plate disposed ahead of the securing station, means for reciprocating the pusher plate to cause it to slide the body members in the pockets into preassembly engagement with the end closure members, a chucking pusher plate at the securing station for pushing the pre-assembled body and closure members against the chuck, and means for reciprocating the chucking pusher plate.

7. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed separable jaw elements in part defining each disk pocket and having closure edge retaining grooves therein, a container body supporting plate spaced along the turret axis from said disk and having peripheral pockets therein aligned with said disk pockets and cooperating therewith in supporting container bodies for sliding movement toward closures positioned in said jaw grooves, means

for securing the closure members to the body members at the securing station and including a chuck engageable by preassembled closure and body members for definitely placing said pre-assembly relative to said securing means, a pre-assembling pusher plate disposed ahead of the securing station, means for reciprocating the pusher plate to cause it to slide the body members in the pockets into preassembly engagement with the end closure members, a chucking pusher plate at the securing station for pushing the preassembled body and closure members against the chuck, means for reciprocating the chucking pusher plate, and means at the securing station for forcing the there presented jaw elements apart to free the closure member edges therebetween prior to the chucking of said body and closure members.

8. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed separable jaw elements in part defining each disk pocket and having closure edge retaining grooves therein, a container body supporting plate spaced along the turret axis from said disk and having peripheral pockets therein aligned with said disk pockets and cooperating therewith in supporting container bodies for sliding movement toward closures positioned in said jaw grooves, means for securing the closure members to the body members at the securing station and including a chuck engageable by preassembled closure and body members for definitely placing said pre-assembly relative to said securing means, a pre-assembling pusher plate disposed ahead of the securing station, means for reciprocating the pusher plate to cause it to slide the body members in the pockets into preassembly engagement with the end closure members, a chucking pusher plate at the securing station for pushing the preassembled body and closure members against the chuck, means for reciprocating the chucking pusher plate, and means for adjusting each of the pusher plates with relation to its reciprocating means to adapt them for engagement with container members of different sizes.

9. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed separable jaw elements in part defining each disk pocket and having closure edge retaining grooves therein, a container body supporting plate spaced along the turret axis from said disk and having peripheral pockets therein aligned with said disk pockets and cooperating therewith in supporting container bodies for sliding movement toward closures positioned in said jaw grooves, means for securing the closure members to the body members at the securing station and including a chuck engageable by preassembled closure and body members for definitely placing said pre-assembly relative to said securing means, a pre-assembling pusher plate disposed ahead of the se-

curing station, means for reciprocating the pusher plate to cause it to slide the body members in the pockets into preassembly engagement with the end closure members, a chucking pusher plate at the securing station for pushing the preassembled body and closure members against the chuck, means for reciprocating the chucking pusher plate, means for adjusting each of the pusher plates with relation to its reciprocating means to adapt them for engagement with container members of different sizes, and a stationary plate sector interposed between the two pusher plates in the direction of travel of the turret structure and having a guide face portion flush with the container body engaging face of the chucking plate when the chucking plate is in its retracted position and flush with the container body engaging face of the preassembling plate when the preassembling plate is in its projected position, and means adjustably supporting said plate sector also being so as to enable retention of said face alignment relation of said plate sector said preassembling pusher plate and said chucking pusher plate.

10. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, opposed jaw elements in part defining each disk pocket and having closure edge retaining grooves therein, and a container body supporting plate spaced along the turret axis from said disk and having peripheral pockets therein aligned with said disk pockets and cooperating therewith in supporting container bodies for sliding movement toward closures positioned in said jaw grooves, said jaws being circumferentially slidable for movement into and out of the normal end closure retaining position, spring means normally holding said jaws in the normal position, assembled container and closure securing means opposed to the turret at the securing station and including a chuck engageable by the container and closure assembly for definitely placing said assembly relative to

said securing means, a reciprocably mounted plate member at the securing station engageable between the opposed and grooved jaws presented thereto for separating said jaws and completing the then presented pocket, and means at said securing station for forcing the body and closure assembly against the chuck.

11. In a machine of the character described, a turret rotatable step-by-step about a horizontal axis and having a plurality of equidistantly spaced pockets in the periphery thereof to receive an end closure and a container body spaced from the end closure in the particular pocket, said end closure having a central depression providing a heel snugly receivable in the container body end, a preassembly station, means effective while the turret is at rest at said station for bringing about relative movement between the end closure and container body in the pocket at that station for preassembling said end closure and container body by causing the heel to snugly engage in said body end, and means effective at another station for securing the assembly of the bodies and closures while they are in the pockets.

12. In a machine of the character described, a turret structure comprising a circular disk having a plurality of equidistantly spaced container body receiving pockets in its periphery, means mounting the turret for rotation about a horizontal axis, means for indexing turret for presenting the disk pockets at container closure and body receiving stations and at assembled container securing and discharging stations, means on said disk for receiving and supporting a container closure in registry with each pocket therein, and a container body supporting plate spaced along the turret axis from said disk and having peripheral pockets therein aligned with said disk pockets and cooperating therewith in supporting container bodies for sliding movement toward closures positioned in said jaw grooves, and means for holding the supporting plate at various distances from the disk for properly supporting container bodies of different length, said last named means including the hub on which the plate is removably mounted, and a plurality of spacer rings of different length surrounding said hub with the plate between selected pairs thereof.

OTTO A. SCHMITT.
